UNITED STATES PATENT OFFICE.

GUY C. HOWARD, OF EVERETT, WASHINGTON.

TUBE-MILL.

1,146,760.

Specification of Letters Patent. Patented July 13, 1915

Application filed June 7, 1913. Serial No. 772,239.

To all whom it may concern:

Be it known that I, GUY C. HOWARD, a citizen of the United States, residing at Everett, in the county of Snohomish and State of Washington, have invented certain new and useful Improvements in Tube-Mills, of which the following is a specification.

This invention relates to improvements in apparatus for the production of fiber from wood or similar substances and particularly to improvements in the devices heretofore patented or applied for by me in which a reduction mill of the tube mill type is utilized to obtain the required disintegration. Said patents and applications are as follows: United States Patents Nos. 997,064, dated July 4, 1911 and 1,039,286, dated Sep. 24, 1912; and patent application, Serial No. 717,035.

The object of the present invention is the provision of improved devices for effecting the discharge of the product of a mill to automatically regulate the level of the material under treatment within the mill to a desired height as predeterminedly adjusted by the operator.

It has been found by experiment in disintegrating wood-fiber in a mill using balls or pebbles as a reducing agent, that to assure a maximum reducing action on the material in its passage through the mill, the height of the charge in the mill—that is to say, the amount of water and fibrous material, must be kept within a certain range. Too large a charge in the mill reduces the efficiency of the grinding forces and too low a charge reduces the capacity and output. The best results are obtained when the charge is of the proper fluidity and approximately fills the interstices of the pebble load. Thus, when the mill is in revolution the pebbles tend to climb upon the "up" side of the mill while a liquid bath free from pebbles is maintained on the "down" side of the mill. An opportunity is thus afforded for the material to partially free itself from the pebbles at each revolution, prevents "matting" of the fibers and assists in the progress of the material through the mill.

The present invention consists in the novel construction of an adjustable discharge regulator, and the combination and adaptation of the same to a tube-mill whereby the desired level of the charge within a mill will be automatically maintained, as will be fully

described in the following specification, illustrated in the accompanying drawings, and finally set forth in the appended claims.

In said drawings, Figure 1 is a side elevation of a tube-mill and devices embodying my invention. Fig. 2 is a longitudinal section of the discharge end of a mill, as illustrated in Fig. 1. Fig. 3 is a cross-sectional view on the line 3—3 of Fig. 2 with the casting partly broken away. Fig. 4 is a horizontal sectional view taken on the axis of the mill. Fig. 5 is a fragmentary view to an enlarged scale of the screen-plate and connected parts, shown partly in section.

Referring to said views, the reference numeral 1 designates the cylindrical barrel of a tube-mill of the type described in my said prior patents. Heads 2 and 3 respectively form the opposite ends of the mill having each an axially arranged hollow trunnion 2¹, 3¹ through which the material to be reduced is respectively fed and discharged. The former trunnion is connected with a feed-hopper 4 while the latter trunnion communicates with discharge regulating apparatus hereinafter described and forming the particular subject matter of this application. Said trunnions are rotatably mounted in standards 5 of a supporting frame and the mill is rotated, as shown, by a power driven pinion 6 in engagement with a circular rack 7 on the exterior of the mill. Within the mill in proximity of its discharge end is a screen-plate 8 spaced apart from said header 3 to afford a chamber 9 and formed with numerous apertures 10 adjacent its circumferential edge affording communication between said chamber and the grinding compartment of the mill. A plurality of radially directed ribs 11 integrally or otherwise rigidly connected to said plate divide said chamber into a number of segmental pockets extending from the periphery of the plate to a centrally arranged chambered hub 12. Certain of said ribs are extended, as at 11¹, into the trunnion 3¹ and terminate therein in chamfered edges 11².

The reference numeral 13 indicates an open receptacle rigidly secured to the frame 5 and formed with an aperture in its end wall 14 to receive the extremity of said trunnion 3. One or both of the side walls 15 are provided with an adjustable outlet for the discharge of the ground material from the mill and each comprises a rectangular

opening from the top of the wall, its opposite vertical edges having grooves 16 formed therein to receive a plurality of slides 17 in superposed order. Said slides are desirably 5 of metal plate and are rectangular in configuration so that when placed in operative position their adjacent edges meet and stop the flow of material therebetween. The material discharged from the mill overflows 10 the topmost slide into a launder or other suitable receiver, not shown. A drain aperture is provided in the bottom of the receptacle which is normally closed by a screw-plug 20.

15 The operation of the invention may be described as follows: The material to be ground, consisting of chipped wood, straw or other fibrous material, is introduced into the mill through the hopper 4 with a supply 20 of water apportioned to obtain the most efficient disintegrating action from the balls contained within the barrel. As the material progresses through the mill it is gradually reduced in size and additional water 25 is introduced within the mill to maintain the proper degree of fluidity suited to the best results. This water may be injected through pipe 18 extending through a stuffing-box 19 in the receptacle 13 and communicating 30 with the interior chamber of said hub 12 whence radially directed tubes, not shown, may conduct the water into the interior of the mill.

In the operation of the mill the material 35 issues through the apertures 10 from the grinding chamber of the mill on the side of the screen-plate that is lowermost and flows into the chamber 9 where it is elevated by being trapped by the ribs in said segmental 40 pockets and carried by the continued rotation of the mill to the top of its cycle of revolution. On its elevation above the axis of the mill the material flows into the non-apertured portion of the screen and finds its 45 outlet through the trunnion 3 whence it flows into the receptacle 13 and overflows the strips. A portion of the material thus elevated will flow backward from the interior of the trunnion through its opening 50 into the lower portion of the chamber 9 to be elevated again with the material therein upon the continued rotation of the mill.

The higher the level of material in the barrel of the mill, the larger the quantity 55 that will pass through the screen and the greater the height such material will assume in said segmental pockets above the overflow discharge and therefore the more force in the flow of discharging material and a 60 larger quantity emitted from the discharge receptacle. The height of the material in the pockets above the discharge, constituting the effective hydraulic head, does not vary to a great degree whatever the height to 65 which the slides 17 may be built up, as the

flow from said head through the trunnion to the overflow is modified by a backward current from the trunnion into the lower pockets where an excessive quantity of material is being passed. The chief factor is 70 the uniformity of discharge regardless of temporary conditions of feed or other causes within the mill making for a uniform high quality of product and a maximum quantity of output.

75 The provision of a discharge outlet above the level of the discharge orifice, in this case the trunnion 3¹, and the utilization of the hydraulic forces in the discharging liquid material, provides a novel method of maintaining practically uniform conditions within the mill by balancing the feed and discharge functions thereof.

80 In practical operation, after once established the slides 17 are rarely changed in height, the height at which the overflow discharge occurs, the main condition for the attainment of the best results being that the discharge does not flow outwardly of the trunnion or other outlet directly by gravity but is effected by the variation in gravity of two columns of liquid and hence a time element is introduced and other balancing factors that insure reasonably uniform results.

85 Discharge apparatus of the type described is particularly well adapted for use with mills having material of a light and bulky character and which require large amounts of water for treatment. For most minerals or other material of a relatively high specific gravity, the apparatus would be unsuited, save for grinding asbestos rock down to its fibrous condition.

100 What I claim is:

1. The combination of a rotatable mill 105 adapted to treat wet material, said mill having a discharge orifice in its axis of rotation, devices for elevating said material above said orifice to obtain a hydraulic head therefor to cause the material to flow by gravity 110 through said orifice, and a receptacle into which said material is discharged having an outlet adjustable in height above said orifice to regulate the said hydraulic head and thereby govern the outflow of material through 115 the mill.

2. The combination of a rotatable mill 120 adapted to treat wet material, having a discharge orifice in its axis of rotation, a screen-plate dividing said mill into a treating compartment and a discharging chamber, said plate being provided with radially directed ribs adapted to elevate the material above said orifice to obtain a hydraulic head therefor to cause it to flow by gravity 125 through said orifice, a receptacle communicatively connected to said orifice to receive said discharge material having an outlet above the bottom of said orifice.

3. The combination of a rotatable mill 130

adapted to treat wet material, having a discharge orifice in its axis of rotation, a screen-plate dividing said mill into a treating compartment and a discharging chamber, said plate being provided with radially directed ribs adapted to elevate the material above said orifice to obtain a hydraulic head therefor to cause it to flow by gravity through said orifice, a receptacle communicatively connected to said orifice to receive said discharge material having an outlet adjustable at various heights above the bottom of said orifice.

4. In combination with a rotatable mill having a hollow trunnion affording the discharge passage of the mill, a screen-plate adjacent said trunnion provided with radial ribs for elevating the material above said orifice, said ribs having their inner ends entered within said trunnion, of a receptacle rigidly secured relative to the rotatable portions of said mill and provided with an outlet above the bottom of said orifice.

5. In a rotatable mill for treating wet material, discharge apparatus therefor consisting in a trunnion having a passage therethrough in the axis of rotation of the mill, a non-rotative receptacle to receive the discharge of material from said passage having its outlet above the bottom of said orifice, and means operable by the rotation of the mill whereby the material within the mill is elevated to obtain an effective hydraulic head for the discharge of said material from said outlet.

6. A rotatable mill for treating wet material having a compartment in which the material is treated, a screen-plate at one end of said compartment affording a chamber to receive the material for discharge, a hollow discharge trunnion in the axis of the mill communicating with said chamber, and a plurality of radially arranged ribs in said chamber extending into said trunnion whereby said material is elevated above said trunnion to obtain a hydraulic head therefor to cause the material to flow by gravity through said trunnion, and a receptacle into which said material is discharged, having an outlet adjustable at various elevations above the bottom of said trunnion.

7. A rotatable mill having, in combination, a compartment in which the material is treated; a chamber at one end thereof, a screen intermediate said compartment and said chamber, a hollow discharge trunnion communicating with said chamber, and a plurality of radial ribs having their inner ends extending within said trunnion for elevating the material above said trunnion.

8. In combination with a rotatable mill, a compartment in which the material is treated, a chamber at one end thereof, a screen intermediate said compartment and said chamber, a hollow discharge trunnion communicating with said chamber, and a plurality of radial ribs for elevating the material above said trunnion, of a receptacle exterior of said discharge trunnion having its outlet elevated above the level of the bottom of said trunnion.

9. In combination with a rotatable mill having a compartment for the treatment of material provided with a feed inlet at one end, a screen at the opposite end of said compartment affording a chamber, a trunnion in the axis of the mill formed with a discharge passage communicating with said chamber, said screen having a hub extending within said trunnion, and radially disposed ribs dividing said chamber into a plurality of segmental shaped pockets, of a receptacle adapted to receive the discharge material from said trunnion having its outlet elevated above the level of the bottom of said trunnion.

10. The combination of a rotatable mill adapted to treat wet material, said mill having a discharge orifice in its axis of rotation, devices for elevating said material above said orifice to obtain a hydraulic head therefor to cause the material to flow by gravity through said orifice, and a receptacle into which said material is discharged having an outlet above said orifice to govern the outflow of material through the mill.

Signed at Oregon City, Oregon, this 21st day of May, 1913.
